TELEPHONE LOCK-OUT.

1,061,898.

Specification of Letters Patent. Patented May 13, 1913.

Application filed February 26, 1907. Serial No. 359,405.

To all whom it may concern:

Be it known that I, WILSON L. CAMPBELL, a citizen of the United States of America, and resident of Chicago, Cook county, Illinois, have invented a certain new and useful Improvement in Telephone Lock-Outs, of which the following is a specification.

My invention relates to automatic telephone exchange systems, and more particularly to automatic party line systems in which means are employed for preventing interference between subscribers on the same line.

In certain respects my invention is in the nature of an improvement on the party line system disclosed in application Serial No. 343,566, filed November 15, 1906, by C. J. Erickson for improvement in party line telephone systems. In said prior application a mechanical locking arrangement is employed for positively locking the calling subscriber's dial against operation should he attempt to use it after some other subscriber on the same line has entered into conversation with a third subscriber on the same line, or with a subscriber on any other line. Also, in the said prior application the current for talking purposes is derived from a common battery at the exchange or central station, and the lock-out devices for the subscriber's telephones are operated by current from the same source.

Objects of my invention are the provision of a dial-locking arrangement which will prevent an intruding subscriber from operating his dial after the party line is in the possession of another subscriber thereon, and before the called subscriber answers; the provision of a dial-locking arrangement for a local battery automatic party line system which will prevent interference between substations on the same party line; and the provision of certain details and features of improvement and combinations tending to increase the general efficiency of a system of this particular character.

To the foregoing and other useful ends, my invention consists in matters herein disclosed and claimed.

The accompanying drawing is a diagram showing two lines (#110 and #210) connected through a central station, either or both of which may be party lines, but only

line #110 at the left being shown as such. At said central office there is also shown a central battery B having its positive terminal preferably grounded at G. Said line #110 is shown provided with two substations (A and A') that are bridged across the line conductors, and the other line #210 is also provided with a substation C. The line #110 is shown connected through the first-selector D and connector E with the second line #210, which latter has bridged across it a first-selector switch F. All of the substations are identical, as well as the first-selector switches; but any of the apparatus may be of any suitable or approved type. The substation in connection with which I have elected to illustrate my invention comprises, for example, a receiver 2, a switch-hook 3 for controlling the substation circuits, which controlling operations are accomplished through the medium of any suitable means, such as the cam-arms 4, 5 and 6. As the switch-hook is lowered, the cam-arm 4 momentarily presses the release springs 7, 8 and 9 into engagement, whereby the substation line conductors may be grounded simultaneously. When the switch-hook is down, the cam-arm 5 engages the spring 10, thereby bridging the ringer 11 in series with the condenser 11^a across the line. Furthermore, when the switch-hook is down the said cam 5 disengages the springs 12, 13 and 14, thus breaking the local circuit which includes in series the primary winding 15, transmitter 16 and local battery 17, and disconnecting the substation locking relay 39 from one side of the line.

The substation ground circuit is normally broken between the ground springs 18 and 19 by the cam-arm 6; but when said springs are together, ground connection is then provided to the ground post 20 and to the release spring 7, as is usually the case in telephones of this type. The said substation comprises the usual induction-coil 21 having the primary winding 15 and secondary winding 22. Being an automatic substation it is provided with the usual vertical and rotary impulse springs 23 and 24. Said substation is, of course, provided with a dial (not shown) which is secured to the shaft 25, together with the locking dog 26. Furthermore, there is a locking cam 27 that

locks the dog 26, while the receiver is on the switch-hook, to prevent a rotation of the dial. For operating the impulse springs 23 and 24 the substation is provided with an impulse wheel 28 that is secured to the shaft 25, which impulse wheel carries on its periphery the so-called vertical impulse teeth 29 and one rotary impulse tooth 30. The said impulse teeth are so arranged that when the dial is rotated the impulse springs 23 and 24 are not carried into contact with the ground post 20; but as the dial returns, first the vertical teeth engage the vertical impulse spring 23, and after they have completed their work the rotary impulse tooth 30 operates the rotary impulse spring 24. In this operation the subscriber's vertical line conductor 31 is first given a number of ground impulses, and then the rotary line conductor 32 is given one ground impulse. It will be noticed that as long as the dial is out of normal position the construction is such that the dog 26 permits the secondary circuit springs 33 and 34 to separate, thus preventing the impulses that are delivered to either line conductor from passing to the other. The substation is further provided with a signaling device that comprises the push button spring 35 which normally engages the contact point 36; but when the button 37 is pressed the spring 35 engages the contact point 38, whereby the vertical line conductor 31 may be grounded. In addition, the substation is provided with a lock-out relay 39 which, when the receiver is removed, is connected between the rotary line conductor 32 and ground G' through the springs 40 and 19. The said relay is provided with an armature 41 pivoted at the point 42, and at its non-pivoted end said armature has a hook. This hook is adapted to engage an eye 43 on the locking dog 26, when the lock-out relay becomes energized, thereby locking the said dog in normal position; and since said dog is rigidly connected to the dial the latter is also locked against operation by the subscriber. The armature 41 is retained in normal position by the retracting spring 44. The first-selector switch shown at D is of the general type described in United States Patent No. 815,321, granted March 13, 1906, to Keith, Erickson & Erickson, having some slight modifications—that is, the rotary side of the line is retained normally open by the switch shaft, instead of being normally closed as is usually the case. It embodies among other details the following well-known devices and circuits: The switch-shaft (not shown) carries the vertical and rotary wipers 45 and 46, respectively, and the private wiper 47. The side switch is well known and comprises the side switch wipers 48, 49, 50 and 51, which may be designated as the vertical, rotary and pri-

vate side switch wipers, and the rotary magnet wiper, respectively. The side switch is under the control of the private magnet 52, and in the normal or first position of the side switch the wipers 48, 49, 50 and 51 occupy the contact points 53, 54, 55 and 56, respectively; in the second position they rest on the contact points 57, 58, 59 and 60, respectively, and in the third position the contact points 61, 62, 63 and 64 are engaged by their respective wipers. Through the medium of the vertical line relay 65, and while the side switch is in first position, the subscriber controls the vertical magnet 66, which latter operates to raise the switch shaft and wipers 45, 46 and 47 vertically. 65 70 75 80

By means of the rotary line relay 67, and while the side switch is in the first position, the subscriber controls the private magnet 52 and, therefore, the side switch. While the side switch is in second position the rotary magnet 68, which operates to carry the switch shaft and wipers 45, 46 and 47 in a rotary direction, is energized. The vertical and rotary line relays 65 and 67, acting conjointly, provide means whereby the subscriber controls the release magnet 68a while the side switch is in the first or second position. If the side switch passes to third position, then, since the selector is of the trunk-release type, the selector is controlled 95 through the next switch (with which latter a connection is then established) and through the private wiper 47 and by means of the back-release relay 69. The bridge-cut-off relay 70 is provided to open the connection between the line relays 65 and 67 and between said relays and battery B. This is desirable, because if the relays are not disconnected from each other and battery the ringing current for signaling the 100 subscriber may operate either or both of the relays 65 and 67, and thus cause some interference with the switch. It is also desirable to remove the bridge formed through the said relays from across the line to give the 110 voice-currents as clear a path as possible. In addition, the said selector switch is provided with a private normal relay 71 by means of which the guarding potential at the connector bank is momentarily removed 115 to enable a subscriber to call back on his own line. The switch shaft also carries the normal arm 72 which, when the shaft is in normal position, retains the spring 73 out of engagement with the spring 74, thus disconnecting the rotary line conductor 32 from the side switch wiper 49; but when the shaft is given its first vertical step the springs 74 and 73 come together. Bridged between the terminals of the relay 71 is the condenser 75, 120 125 used to improve the talking circuit.

The connector switch E may also be of any suitable or approved type, for instance

of the general type described in United States Patent No. 815,176, granted March 13, 1906, to Keith, Erickson & Erickson. The mechanical details of the first-selector and connector, as is well known, are very much the same, although there is some material difference in the circuits. The connector switch shaft (not shown), like the first-selector switch shaft, carries the line wipers 76 and 77 and the private wiper 78. The connector switch is also controlled by the calling subscriber through the medium of the vertical and rotary line relays 79 and 80. The vertical line relay directly controls the 10 vertical magnet 81, and also the rotary magnet 82 and ringer relay 83. The office of the vertical magnet 81 is to give the shaft and shaft wipers their vertical motion; and the rotary magnet 82 imparts to the shaft 20 and shaft wipers a rotary or circular motion. The rotary line relay 80 controls the private magnet 84, which latter, under certain conditions, controls in turn the vertical and rotary magnets 81 and 82, the release magnet 85, and also the side switch wipers 86, 87, 88 and 89. The side switch of the connector, like the side switch of the first-selector, has a normal or first position, a second position and a third position. The 30 release magnet 85 is also controlled by the line relays 79 and 80, conjointly. By the condensers 90 and 91 the circuit through the connector is divided into two sections. The central office is equipped with a busy-signaling apparatus of any suitable design, as, for example, the one comprising an interrupter 92 in series with the primary winding 93 of the induction-coil 94, whereby a busy-signaling current is induced in the secondary winding 95 of the said coil. The connector switch shaft also carries a normal post arm 96 which, when the connector shaft is off normal, allows the spring 97 to engage the contact point 98, whereby a busy-signaling 40 current may be transmitted to the calling subscriber when the side switch is in first position.

The calling operation by which the subscriber A, for example, would call and signal subscriber C is as follows: To call the 50 number 210, which is assumed to be the number of substation C, the subscriber A at substation #110 operates his calling device in a suitable manner corresponding to each 55 digit of the called number. For each digit the vertical line is grounded a certain number of times, corresponding to the numerical value of the digit, and then the rotary side of the line is grounded once. The receiver 60 2 is, of course, first removed from the switch-hook 3, closing in contact the springs 33 and 34 and breaking the contact between the spring 10 and cam-arm 5, thus removing the ringer 11 from across the line and clos-

ing the receiver circuit. The first digit being 2, the subscriber at substation A turns his dial for the first digit 2, thereby grounding the vertical line conductor 31 twice, and the rotary line conductor 32 once upon the return motion of the dial. Grounding the 65 vertical line conductor 31 twice, as explained, energizes the vertical line relay 65 of the first-selector. The circuit through the said vertical line relay extends from ground G' through the ground springs 19 and 18 70 to the ground post 20, thence to the vertical impulse spring 23, vertical line conductor 31 to the side switch wiper 48, contact point 53, through the vertical line relay 65 to the bridge-cut-off springs 99 and 100, 80 to the battery lead 101, thence through battery B to ground G. Each time that the vertical line relay 65 is energized the vertical line relay springs 102 and 103 are pressed into contact, and an energizing circuit is 85 each time established through the vertical magnet 66. The circuit through said magnet extends from ground G' to the relay springs 102 and 103, to the private magnet springs 104 and 105, through the winding 90 of the vertical magnet 66 to the battery lead 101, thence through battery B to ground G. The vertical magnet 66 being operated twice, the first-selector switch shaft and wipers 45, 46 and 47 are raised two steps. The said 95 wipers are carried to a level with the contact points that constitute the terminal of the trunk line leading to the connector switch E. Following the vertical impulse the rotary impulse spring 24 is grounded 100 once by the rotary impulse tooth 30, thereby grounding the rotary line conductor 32 once and energizing the rotary line relay 67. The path of this energizing circuit is from ground G' through the ground springs 19 105 and 18 to the ground post 20, through the rotary impulse spring 24 to the rotary line conductor 32, normal springs 74 and 73, side switch wiper 49, contact point 54 to the rotary line relay 67, thence to the bridge-cut-off springs 106, 99 and 100 and to the battery lead 101, thence through battery B to ground G. The rotary line relay, upon energizing, presses the line relay springs 107 110 and 102 into contact, thereby establishing an energizing circuit through the private magnet 52. The current through said magnet passes from ground G' through the springs 102 and 107 to the private magnet 52 and battery lead 101, thence through battery B 115 and to ground G. The private magnet being energized for a moment, the side switch of the first-selector passes to second position, permitting the side switch wiper 51 to close the energizing circuit through the rotary 120 magnet 68. The current flows from ground G' through the contact point 60, side switch wiper 51 to the interrupter springs 108,

thence through the winding of the rotary magnet 68 to the battery lead 101, thence through battery B and to ground G. The rotary magnet is energized one step, and the 5 shaft wipers 45, 46 and 47 are carried into engagement with the bank contacts that constitute the terminal of a trunk line leading to the connector switch E.

If the first trunk line is busy an energizing 10 circuit is established through the private magnet 52 when the private wiper 47 strikes a grounded contact, thereby retaining the side switch in second position and maintaining the circuit through the rotary magnet 15 68. The rotary magnet, by intermittent energizing, causes the shaft wipers to rotate past the last busy trunk line. However, as soon as the private magnet deenergizes, the side switch is tripped into third position; or, 20 if there are no busy contacts to be passed over, the rotary magnet 68, as is well known, trips the side switch to third position, when the wipers engage the first trunk line, with the result that as soon as the side switch 25 wipers 48 and 49 engage their respective contacts 61 and 62 the subscriber's line is extended to the connector switch E. Also, since the side switch wiper 50 engages the grounded contact point 63, a guarding potential 30 is established at the private wiper 47 for preventing the seized trunk line to the connector E from being molested by any other switch. This guarding potential also protects the calling line by establishing a 35 guarding potential at the connector bank over the private normal conductor 109. The second digit is called after the subscriber has established connection with the connector E by way of the trunk conductors 110 and 111. The subscriber rotates the dial, as 40 described, for the second digit 1, thereby grounding the vertical and rotary line conductors 31 and 32, which causes the energizing of the connector vertical and rotary line 45 relays 79 and 80. The energizing current for this purpose flows over the following path: from ground G' to the vertical line conductor 31 to the side switch wiper 48, contact point 61, shaft wiper 45 to the trunk conductor 110, through the winding of the vertical line relay 79 to the battery lead 101, thence through battery B to ground G. Each time the vertical line relay 79 is energized the line relay springs 112 and 113 are 50 pressed into contact, and an energizing circuit is established each time through the vertical magnet 81. The energizing current through the vertical magnet 81 flows from ground G' to the springs 112 and 113, private magnet springs 114 and 115, side switch wiper 88, contact point 116 to the vertical magnet 81, to the battery lead 101, thence through battery B to ground G. The vertical 55 magnet 81, each time it is energized, raises

the shaft and shaft wipers 76, 77 and 78 one step and opposite a level in which are located the terminals of the line #210. When the rotary line conductor 32 is grounded the rotary line relay 80 becomes energized through the following path: from ground G' to the rotary line conductor 32, normal springs 74 and 73, side switch wiper 49, contact point 62, through the winding of the private normal relay 71, shaft wiper 46, trunk conductor 111, ringer relay springs 117 and 118, through the winding of the rotary line relay 80 to the battery lead 101, thence through battery B and to ground G. The energizing of the rotary line relay 80 causes the springs 119 and 112 to come into contact, thereby completing a circuit through the private magnet 84. The path of the energizing current is from ground G' to the line relay springs 112 and 119, through the winding of the private magnet 84 to the battery lead 101, thence through battery B and to ground G. The momentary energizing of the private magnet 84 causes the release of the side switch from first to second position, thus placing the side switch wipers 88 and 89 in contact with the points 120 and 121, respectively. The last digit being naught the subscriber operates the dial as previously described, grounding the vertical line conductor 31 ten times and the rotary line conductor 32 once. The vertical and rotary line relays 79 and 80 are operated over the previously traced circuits. However, when the line relay springs 112 and 113 engage each other a circuit is closed through the rotary magnet 82, instead of through the vertical magnet 81. The circuit may be traced from ground G' to the line relay springs 112 and 113, private magnet springs 114 and 115, side switch wiper 88, contact point 120, through the rotary magnet 82 to the battery lead 101, thence through battery B to ground G.

Each time that the rotary magnet is energized the rotary armature is attracted and rotates the shaft carrying the wipers 76, 77 and 78 one step at a time, until the said wipers are carried into engagement with the normal conductors 122, 123 and 124, the first two of which lead to the line of the desired subscriber, whose number is 210. The energizing of the rotary line relay 80 for the last digit completes an energizing circuit through the private magnet 84 which now operates with one of two results, namely the release of the side switch from second to third position, or the so-called busy-release of the connector if the called line is busy. Suppose the former result to occur, and the side switch to pass to third position, placing the side switch wipers 86, 87, 88 and 89 in contact with the points 125, 126, 127 and 128, respectively. Furthermore, when the side

switch passes to third position a guarding potential is established for protecting the called line. This potential extends from ground G⁵ to the contact point 128, side 5 switch wiper 89, to the shaft wiper 78 which engages the private contact of the called line. The said engagement of the contact point 128 by the side switch wiper 89 closes an energizing circuit through the bridge-cut-off relay 129 of the first-selector F, thereby disconnecting the vertical and rotary line relays of the first-selector F from each other and from the battery lead. Now, to signal the called subscriber, the calling 10 subscriber presses the signaling button 37, placing the spring 35 in contact with the substation ground G', thereby energizing the vertical line relay 79. The path of the energizing current extends from ground G' to the contact point 38, spring 35, springs 34 and 33 to the vertical line conductor 31, thence through the connector vertical relay 79, as previously traced, to battery B and to ground G. It will be remembered that 15 the connector side switch has passed from second to third position, and that the side switch wiper 88 is in engagement with the contact point 127, thereby placing the vertical line relay 79 in control of the ringer relay 83 in the same manner in which the rotary magnet 82 came under the control of the vertical line relay 79 when the side switch passed from first to second position. Therefore, when the vertical line relay 79 20 presses the springs 112 and 113 into contact the ringer relay 83 is energized by a flow of current from ground G⁴ to the relay springs 112 and 113, private magnet springs 114 and 115, side switch wiper 88, contact point 127 25 to the ringer relay 83 and to the battery lead 101, thence through battery B and to ground G. The ringer relay, upon energizing, disengages the springs 117 and 118 and shifts the springs 129 and 130, respectively, from the springs 131 and 132 onto the springs 133 and 134. This results in separating the calling subscriber's line from the called subscriber's line and bridging across the line of the latter the terminals of the ringer generator H. A signaling current is, therefore, sent from the generator H to the ringer relay springs 134 and 130, side switch wiper 87, contact point 126, connector shaft wiper 77, normal conductor 123, rotary line conductor 135, condenser 136 to the ringer 137, spring 138, switch-hook 139 to the vertical line conductor 140, normal conductor 122, connector shaft wiper 76, contact point 125, side switch wiper 86, ringer relay springs 30 129 and 133 back to the generator H. As soon as the calling subscriber ceases to press the signaling button 37 the ringer relay 83 becomes deenergized, and the springs 129 and 130 resume their normal position in con-

tact with the springs 131 and 132, respectively. The subscriber C, in response to the signal, removes the receiver 141 from the switch-hook 139, thereby removing the ringer 137 from across his line and bridging instead the secondary circuit which includes 65 the condenser 136, receiver 141, secondary winding 142 of the induction-coil 143 and secondary springs 144 and 145. The local transmitter circuit is closed as soon as the springs 146, 147 and 148 engage in contact. 70 The two substations #110 and #210 are now connected over the circuit shown by heavy lines in Fig. 1.

From the preceding it will be seen that a calling line, as well as a called line, is protected against interference by a third line by proper guarding potentials at the connector banks. In a party line system like this, however, it becomes necessary to insure to the subscriber who first obtains control of the line the use of the line without molestation until after he is through calling. The means by which I accomplish this comprises the substation lock-out magnet 154 80 at substation A'. If, after the two subscribers A and C are connected for conversation, as explained, the subscriber at substation A' attempts to make use of the line the magnet 154 energizes and locks the subscriber's dial, and in this way he is prevented from operating his telephone and is thus prevented from interfering with the connection that is already established. It will be understood that the magnet 154 does not energize except when another subscriber 85 on the same line has previously obtained control of the line, as already explained. Assuming that the subscribers A and C are in connection over the circuit mentioned, and that the subscriber A' (who occupies 90 the line in common with A) removes his receiver 149 from the switch-hook 150, as the receiver rises the magnet 154 is energized. The energizing circuit for the said magnet 154 is established at the instant that the 95 springs 152 and 153 come into contact, provided the selector D has operated so that the switch shaft has permitted the switch shaft springs 74 and 73 to close in contact. The energizing circuit for the lock-out 100 magnet extends as follows: from ground G⁶ through the locking relay ground circuit 105 springs 157 and 158, through the magnet 154, springs 152 and 153 to the rotary line conductor 32, thence by any one of the 110 various paths to the non-grounded terminal of battery B. The path by which the current passes from the rotary line conductor 32 to the non-grounded terminal of battery B depends upon the time at which the subscriber A' attempts to come on the line. If 115 he does so before the first-selector side switch has passed from the first position

the path to non-grounded battery is as follows: through the switch shaft springs 74 and 78, side switch wiper 49 and rotary line relay 67, bridge-cut-off relay springs 106, 5 99 and 100 to the battery lead 101. If he comes in when the side switch is in second position the path to the battery extends from the side switch wiper 49 through the vertical line relay 65; and if while the side 10 switch is in third position the path to non-grounded battery is through the private normal relay 71, through the ringer relay springs 117 and 118 and vertical line relay 80 of the connector. When the magnet 154 15 energizes it attracts its armature 155, which armature then engages the eye of the cam-dog 156; and since the said dog 156 is rigidly connected to the shaft upon which the dial is mounted, the subscriber is unable 20 to turn the dial as long as the said magnet 154 is energized. The construction of the 25 substation (referring to substation A) is such that when the receiver is on the switch-hook the cam 6 retains the ground spring 19 away from the locking cam 27, which latter then drops to its normal position, as indicated at substation C; and in this position an insulating tip carried by said cam 27 falls in front of the angled terminal of the 30 ground spring 19, whereby the said spring 19 is retained in engagement with the locking magnet spring 40 while the receiver is on the switch-hook, and even after the switch-hook rises, and until after the dial 35 is rotated. When the dial is rotated the cam 27, which has been previously raised by the cam-arm 6 of the switch-hook, so as to clear the cam-dog 26 enough to enable the dial to be rotated as shown at A', is still 40 further raised by the pin on the end of the cam-dog 26; at which time the insulating tip on the end of the locking dog 27 clears the angled terminal of the ground spring 19, which spring then leaves the locking magnet 45 spring 40 and passes into engagement with the spring 18, from which connection is made to the ground contact of the push button 37 and to the ground release spring 7. It will be evident, then, that until the dial 50 has been rotated it is impossible for the subscriber to send impulses to the line by either working his switch-hook up and down and thereby pressing the release springs together, or by pressing his signaling button. 55 Therefore, it becomes evident that if the subscriber A' comes on the line after the subscriber at substation A has operated the selector D the magnet 154 will lock the dial and prevent him from sending ground impulses to the line conductors 31 and 32. 60 When the subscriber at substation A' learns that he can make no connection he will, of course, hang up his receiver, by which operation the springs 152 and 153 are sepa-

rated and the energizing circuit of the magnet 154 broken. Said magnet, upon de-energizing, of course, permits its armature 155 to recede from the dog 156, thus restoring the substation to its normal condition. 65

Having thus described how a second subscriber on the calling line is prevented from interfering with an established connection, it will be well to point out how a second subscriber on the called line is prevented from interfering with the connection. It 70 has been described that as soon as the connector completes connection with the desired line, the bridge-cut-off relay 129^a energizes and disconnects the line relays of the selector F from each other and from the battery 80 lead. Furthermore, it will be evident that in the connector there is no connection between the main line of the called subscriber and the non-grounded terminal of the battery on the called side of the condensers 90 85 and 91. Therefore, a second subscriber on a called line may come in on the line and operate his telephone if he chooses; but he cannot interfere with the connection, because the ground impulses do not reach the 90 battery. 90

Having thus described the non-interfering feature of my system I will now describe how the calling subscriber destroys the established connection with the called 95 line after he is through talking. Having decided to disconnect, he hangs his receiver 2 upon the switch-hook 3, which latter, upon descending, presses the release springs 7, 8 and 9 into contact. The contact of the said 100 release springs grounds the vertical and rotary line conductors 31 and 32 simultaneously from ground G' to the release spring 7, thence through the springs 8 and 9 to the vertical and rotary line conductors, 105 thereby simultaneously energizing the vertical and rotary line relays 79 and 80 of the connector E, whereby the trunk-release springs 159 and 160 are brought into contact, closing a circuit through the release 110 relay 69 of the first-selector D in series with the release magnet 85 of the connector E. The path of the circuit extends from ground G' to the contact point 63, side switch wiper 50, release relay 69, first-selector switch 115 shaft wiper 47, connector trunk-release springs 159 and 160, release magnet 85 to the battery lead 101, thence through battery B and to ground G. When the connector release magnet 85 is thus supplied 120 with current it energizes, and as a result the switch shaft and side switch are restored to normal position, thus breaking the connection between the connector switch shaft wipers 76, 77 and 78 and the normal conductors 122, 123 and 124. The back-release relay 69 of the first-selector D, being in the 125 same circuit with the release magnet 85,

energizes simultaneously with the latter and presses the springs 161 and 162 into engagement, which in turn closes an energizing circuit through the release magnet 68^a of the first-selector D. This circuit extends from ground G^a through the release relay springs 161 and 162, through the winding of the release magnet 68^a to the battery lead 101, thence through battery B and to ground 5 G. The release magnet 68^a thus energized attracts its armature and remains in readiness to release the selector switch as soon as the substation release springs 7, 8 and 9 10 separate and break the ground connection 15 with the line conductors 31 and 32. Not only does this release magnet deenergize, but all other magnets as well, leaving the apparatus fully restored. The calling subscriber thus restores all switching apparatus 20 which he originally brought into use. To call any subscriber not on his own line, the calling subscriber will bring about the operation as described; but a subscriber like the subscriber at substation A may also call 25 another subscriber on his own line. For instance, suppose the subscriber A desires to signal a subscriber occupying the same line as subscriber A'. In this case the calling and called lines are identical, but a 30 special provision is made in the first-selector switch to momentarily remove the guarding potential established at the connector bank and thus allow a subscriber to call back on his own line. When the last rotary impulse 35 is sent over the line, the private normal relay 71 becomes energized; thus the springs 163 and 164 disengage and remove the guarding potential from the connector bank. The impulse to the rotary line removes the 40 protecting potential which would cause the busy-release of the connector, and the connector private magnet 84 operates to release the side switch to third position. It is evident, therefore, that a subscriber calling 45 another subscriber on his own line would never get a busy-release.

The subscriber A having connected the switching apparatus at the central station with his own line, by pressing the signaling button a suitable number of times sends signaling current impulses out on his line, ringing the different substation bells which are bridged across the called line. The subscriber at A' recognizes his substation signal (two rings, for instance) and removes his receiver from the switch-hook, and when the springs 152 and 153 engage, an energizing circuit is established through the locking relay 154 which operates as explained. Thus it will be seen that any subscriber may call his own line, inasmuch as the connector switch E used in this case will not be automatically released as soon as it engages the multiple line terminal connect-

ed with the line from which the call came. 65 The two subscribers who are conversing on the same line are safe from intrusion or molestation to this extent, namely that no other subscriber can use the line for switching or signaling purposes, since no other 70 subscriber on the same line can operate his telephone or calling device to endanger the continuity of the circuit established between the two subscribers who are talking, because the selector switch D is off normal, and an 75 energizing circuit is established through the lock-out relay of the third subscriber's substation as soon as his switch-hook rises. It will be evident that the release, when a subscriber has called back upon his own line, 80 is the same as in any other instance—that is, when one subscriber has called another subscriber on his own line, the calling subscriber may release the switching apparatus by grounding the line conductors 31 and 32 85 when the receiver is hung on the hook, at which time the line relays 79 and 80 of the connector E are energized simultaneously and the usual release circuit established. The bridge-cut-off relay of the first-selector 90 of the called line does not energize when the connector calls back on the calling line, since the side switch wiper 50 of the first-selector D is in third position. However, when any other line is called the bridge-cut-off relay 95 of the called line is bound to energize, as explained, as soon as a connector side switch passes to third position; but the energizing circuit is broken as soon as the connector releases, thus restoring the selector of the 100 called line to the control of the subscriber or subscribers thereof.

From the foregoing it will be seen that I provide a dial-locking arrangement which is effective for locking out an intruding subscriber before the called subscriber answers. In this way a calling subscriber on a party line is safe against interference after he has brought the individual switch of the line to an off-normal position, and before the called 110 subscriber answers. In other words, it is not necessary for the called subscriber to answer in order to protect the calling subscriber against interference by some other subscriber on the same line. Furthermore, 115 the dial-locking arrangement is not operated by current which is put on the line for talking purposes, but to the contrary is dependent upon a special flow of current in the party line, the current for talking purposes 120 being supplied from local batteries. It will also be seen that with this arrangement the dial of a party properly in possession of the line is not locked, and that only the dial of the intruding subscriber becomes locked 125 when he attempts to interfere with the first party in the use of the line. As stated, however, an important feature of my present

invention is the locking out of intruding subscribers before the called subscriber answers. Obviously, this is an important consideration, because with such arrangement a calling party line subscriber is safe against interference practically as soon as he begins using the line.

What I claim as my invention is:

1. In a telephone exchange system, the combination of a telephone line, a plurality of subscribers' calling dials on said line, means responsive to the operation of said dials, adapted for automatically connecting a calling subscriber with a called subscriber, a subscriber's transmitter associated with each calling dial, a local battery for each transmitter, a locking device for each dial; and means for operating the locking device of an intruding subscriber.
2. In a telephone exchange system, the combination of a telephone line, a plurality of subscribers' calling dials on said line, means responsive to said calling dials, adapted for automatically connecting a calling subscriber with a called subscriber, a locking device for each dial, and means for operating the locking device of an intruding subscriber before the called subscriber answers.
3. In a telephone exchange system, the combination of a telephone line, a plurality of subscribers' calling dials on said line, a locking device for each dial, means responsive to the operation of said dials, adapted for automatically connecting a calling subscriber with a called subscriber, each locking device including an electromagnet, a normally open ground circuit for energizing each electromagnet, and means for closing the ground circuit to energize the magnet and thereby lock the dial of an intruding subscriber.
4. In a telephone exchange system, the combination of a telephone line, a plurality of subscribers' calling dials on said line, means responsive to the operation of said dials for automatically connecting a calling subscriber with a called subscriber, a locking device for each dial, each locking device including an electromagnet, a normally open ground circuit for energizing each magnet, each subscriber provided with a switch-hook controlling the ground circuit through his allotted electromagnet.
5. In a telephone exchange system, the combination of a telephone line, a plurality of calling dials on said telephone line, means responsive to the operation of said dials, adapted for automatically connecting a calling subscriber with a called subscriber, a locking device for each dial, adapted when operated to positively lock the dial against rotation, and means for operating the locking device of an intruding subscriber as
- soon as the calling subscriber by operating his dial sends in an initial impulse.
6. In a telephone exchange system, the combination of a telephone line having one side thereof normally open, a plurality of calling dials on said line, a locking device for each dial, means responsive to the operation of said dials, adapted for automatically connecting a calling subscriber with a called subscriber, and including means for closing the said normally open side of the line as soon as the calling subscriber begins calling, and means for operating the locking device of an intruding subscriber over a circuit including the said normally open side of the line.
7. In a telephone exchange system, the combination of a telephone line, an automatic switch individual to said line, a plurality of calling dials on said line, impulse-transmitting means responsive to the operation of said dials, a locking device for each dial, and means for operating the locking device of an intruding subscriber as soon as the said individual switch is in an off-normal condition.
8. In a telephone exchange system, the combination of a telephone line, a plurality of calling dials on said line, impulse-transmitting means responsive to the operation of said dials, a locking device for each dial, parallel circuits for operating said locking devices, one side of the line being common to all of said circuits, and each circuit including the ground, and means for closing the circuit of an intruding subscriber to prevent interference with the subscriber already in possession of the line.
9. A telephone exchange system comprising a calling dial, a locking device for said dial, said locking device including an electromagnet, a normally open ground circuit for energizing said magnet, a switch-hook associated with the said dial, a telephone line, and means for closing said circuit by the operation of the switch-hook if the line is already in the possession of another subscriber.
10. In a telephone exchange system, the combination of a telephone line, a plurality of subscribers' calling dials on said line, means including switches having vertical and rotary motion responsive to the operation of said dials, adapted for automatically connecting a calling subscriber with a called subscriber, trunk-release circuits therefor, a subscriber's transmitter associated with each calling dial, a local battery for each transmitter, a locking device for each dial, and means for operating the locking device of an intruding subscriber.
11. In a telephone exchange system, the combination of a telephone line, a plurality of subscribers' calling dials on said line,

means including switches having vertical and rotary motion responsive to said calling dials, adapted for automatically connecting a calling subscriber with a called subscriber, 5 trunk-release circuits therefor, a locking device for each dial, and means for operating the locking device of an intruding subscriber before the called subscriber answers.

12. In a telephone exchange system, the 10 combination of a telephone line, a plurality of subscribers' calling dials on said line, a locking device for each dial, means including switches having vertical and rotary motion responsive to the operation of said 15 dials, adapted for automatically connecting a calling subscriber with a called subscriber, trunk-release circuits therefor, each locking device including an electromagnet, a normally open ground circuit for energizing 20 each electromagnet, and means for closing the ground circuit to energize the magnet and thereby lock the dial of an intruding subscriber.

13. In a telephone exchange system, the 25 combination of a telephone line, a plurality of subscribers' calling dials on said line, means including switches having vertical and rotary motion responsive to the operation of said dials for automatically connecting 30 a calling subscriber with a called subscriber, trunk-release circuits therefor, a locking device for each dial, each locking device including an electromagnet, a normally open ground circuit for energizing 35 each magnet, each subscriber provided with a switch-hook controlling the ground circuit through his allotted electromagnet.

14. In a telephone exchange system, the 40 combination of a telephone line, a plurality of calling dials on said telephone line, means including switches having vertical and rotary motion responsive to the operation of 45 said dials, adapted for automatically connecting a calling subscriber with a called subscriber, trunk-release circuits therefor, a locking device for each dial, adapted when operated to positively lock the dial against rotation, and means for operating the locking device of an intruding subscriber as soon 50 as the calling subscriber by operating his dial sends in an initial impulse.

15. In a telephone exchange system, the 55 combination of a telephone line having one side thereof normally open, a plurality of calling dials on said line, a locking device for each dial, means including switches having vertical and rotary motion responsive to the operation of said dials, adapted for automatically connecting a calling subscriber with a called subscriber, and including means for closing the said normally open side of the line as soon as the calling subscriber begins calling, trunk-release circuits therefor, and means for operating the

locking device of an intruding subscriber 65 over a circuit, including the said normally open side of the line.

16. In a telephone exchange system, the 70 combination of a telephone line, an automatic switch individual to said line, a plurality of calling dials on said line, means having first one motion to select groups and then rotary motion to connect with a line in the selected group responsive to the operation of said dials, trunk-release circuits 75 therefor, a locking device for each dial, and means for operating the locking device of an intruding subscriber as soon as the said individual switch is in an off-normal condition.

17. In a telephone exchange system, the 80 combination of a telephone line, a plurality of calling dials on said line, means having first one motion to select groups and then rotary motion to connect with a line in the 85 selected group responsive to the operation of said dials, trunk-release circuits therefor, a locking device for each dial, parallel circuits for operating said locking devices, one side of the line being common to all of said 90 circuits, and each circuit including the ground, and means for closing the circuit of an intruding subscriber to prevent interference with the subscriber already in possession of the line.

18. A telephone exchange system comprising a calling dial, means responsive thereto having a straight motion to select groups and a rotary motion to connect with a line in the selected group, a locking device for said dial, said locking device including an electromagnet, a normally open ground circuit for energizing said magnet, a switch-hook associated with the said dial, a telephone line, and means for closing said 105 circuit by the operation of the switch-hook if the line is already in the possession of another subscriber.

19. In a telephone trunking system, subscribers' lines divided into groups, the combination of a telephone line, a plurality of subscribers' calling dials on said line, means responsive to the operation of said dials having first vertical motion to select groups and then rotary motion to connect with a 110 line in any predetermined group, adapted for automatically connecting a calling subscriber with a called subscriber, a subscriber's transmitter associated with each calling dial, a local battery for each transmitter, 115 a locking device for each dial, and means for operating the locking device of an intruding subscriber.

20. In a telephone trunking system, subscribers' lines divided into groups, the combination of a telephone line, a plurality of subscribers' calling dials on said line, means responsive to said calling dials having first

- vertical motion to select groups and then rotary motion to connect with a line in any predetermined group, adapted for automatically connecting a calling subscriber with a called subscriber, a locking device for each dial, and means for operating the locking device of an intruding subscriber before the called subscriber answers.
21. In a telephone trunking system, subscribers' lines divided into groups, the combination of a telephone line, a plurality of subscribers' calling dials on said line, a locking device for each dial, means responsive to the operation of said dials having first vertical motion to select groups and then rotary motion to connect with a line in any predetermined group, adapted for automatically connecting a calling subscriber with a called subscriber, each locking device including an electromagnet, a normally open ground circuit for energizing each electromagnet, and means for closing the ground circuit to energize the magnet and thereby lock the dial of an intruding subscriber.
22. In a telephone trunking system, subscribers' lines divided into groups, the combination of a telephone line, a plurality of subscribers' calling dials on said line, means responsive to the operation of said dials having first vertical motion to select groups and then rotary motion to connect with a line in any predetermined group, adapted for automatically connecting a calling subscriber with a called subscriber, a locking device for each dial, each locking device including an electromagnet, a normally open ground circuit for energizing each magnet, each subscriber provided with a switch-hook controlling the ground circuit through his allotted electromagnet.
23. In a telephone trunking system, subscribers' lines divided into groups, the combination of a telephone line, a plurality of calling dials on said telephone line, means responsive to the operation of said dials having first vertical motion to select groups and then rotary motion to connect with a line in any predetermined group, adapted for automatically connecting a calling subscriber with a called subscriber, a locking device for each dial adapted when operated to positively lock the dial against rotation, and means for operating the locking device of an intruding subscriber as soon as the calling subscriber by operating his dial sends in an initial impulse.
24. In a telephone trunking system, subscribers' lines divided into groups, the combination of a telephone line having one side thereof normally open, a plurality of calling dials on said line, a locking device for each dial, means responsive to the operation of said dials having first vertical motion to select groups and then rotary motion to connect with a line in any predetermined group, adapted for automatically connecting a calling subscriber with a called subscriber, and including means for closing the said normally open side of the line as soon as the calling subscriber begins calling, and means for operating the locking device of an intruding subscriber over a circuit including the said normally open side of the line.
25. In a telephone trunking system, subscribers' lines divided into groups, the combination of a telephone line, an automatic switch individual to said line, a plurality of calling dials on said line, means responsive to the operation of said dials having first vertical motion to select groups and then rotary motion to connect with a line in any predetermined group, a locking device for each dial, and means for operating the locking device of an intruding subscriber as soon as the said individual switch is in an off normal condition.
26. In a telephone trunking system, subscribers' lines divided into groups, the combination of a telephone line, a plurality of calling dials on said line, means responsive to the operation of said dials having first vertical motion to select groups and then rotary motion to connect with a line in any predetermined group, a locking device for each dial, parallel circuits for operating said locking devices, one side of the line being common to all of said circuits, and each circuit including the ground, and means for closing the circuit of an intruding subscriber to prevent interference with the subscriber already in possession of the line.
27. In a telephone trunking system, lines divided into groups, a plurality of calling dials, a locking device on each dial, a selector switch having motion in one plane to select groups and then motion in a plane at right-angles thereto to select a line in any predetermined group, said switch being responsive to the operation of said dial, a side switch for said selector switch having three operative positions, and means for operating said locking device when said side switch is in its first, second or third position, substantially as described.
28. In a telephone trunking system, lines divided into groups, a plurality of calling dials, a locking device on each dial, a selector switch and a connector switch having motion in a plane to select groups and then motion in a plane at right-angles thereto to select a line in any predetermined group, said connector switch being responsive to the operation of said dial, a side switch for said connector switch having three operative positions, and means for operating said

locking device when said side switch is in its first, second or third position, substantially as described.

29. In a telephone trunking system including party-lines, a plurality of calling dials for each of said lines, a locking device for each dial, an automatic switch, a side switch therefor, and means for operating said locking device when the side switch is 10 in any one of its operative positions, substantially as described.

30. In a telephone system, a switch hook,

a calling dial, and a locking magnet therefore adapted to be energized as soon as the switch hook rises by establishing a circuit 15 from ground to the line, substantially as described.

Signed by me at Chicago, Cook county, Illinois, this 20th day of February, 1907.

WILSON L. CAMPBELL.
